UNITED STATES PATENT OFFICE.

ALVA L. SCHULTZ, OF POCAHONTAS, IOWA.

SASH-HANGER.

1,331,678.

Specification of Letters Patent. Patented Feb. 24, 1920.

Application filed July 16, 1919. Serial No. 311,375.

To all whom it may concern:

Be it known that I, ALVA L. SCHULTZ, a citizen of the United States, and resident of Pocahontas, in the county of Pocahontas and State of Iowa, have invented a certain new and useful Sash-Hanger, of which the following is a specification.

The object of my invention is to provide a sash hanger of simple, durable and inexpensive construction.

More particularly, it is my object to provide a device comprising two members, one of said members being adapted to be permanently fixed to a window casing, and a second member being adapted to be permanently fixed to a sash; the parts being so arranged that the sash may be quickly and easily either attached or detached from the window casing.

A further object of my device is to provide a member adapted to be permanently fixed to a window casing or the like, a second member adapted to be fixed to a sash; the parts of said members being so arranged that pivotal movement of said members relative to each other is permitted.

A further object of my device is to provide a member adapted to be permanently fixed to a casing or the like, a second member adapted to be fixed to a sash; a locking or closure member on said first member adapted to hold said second member from accidental displacement relative to said first member, but permitting pivotal movement of said members relative to each other.

A further object of my device is to provide a member or a base adapted to be fixed to a window casing or the like, said member having spaced lugs thereon, a hook member formed on the lower end of said member, a second member adapted to be fixed to a sash or the like. The said members being designed to coact, whereby pivotal movement of said second member is had relative to said first member. A locking device on said first member for holding said members in proper relationship to each other.

With these and other objects in view, my invention consists in the construction, arrangement and combination of the various parts of the device, whereby the objects contemplated are attained, as hereinafter more fully set forth, pointed out in my claims, and illustrated in the accompanying drawings, in which:

Figure 1 shows a front elevation of a sash

and window casing, having my improved sash hanger thereon.

Fig. 2 shows a sectional view on line 2—2 of Fig. 1, showing a side view of the device.

Fig. 3 shows a plan view of the device, a closure member being shown in one of its dotted positions.

Fig. 4 shows a sectional view on the line 4—4 of Fig. 1, showing a central, sectional view through the device.

Fig. 5 shows a plan view of the device, showing the closure member in one position.

Fig. 6 shows a view of the member having the closure device thereon.

Fig. 7 shows a side view of the device in its nested form for shipment.

In the accompanying drawings, I have used the reference numeral 10 to indicate a window casing or the like in general. 75 Mounted in the casing 10 is a sash 11, having a screen 12 thereon. Secured to the casing or frame 10 is a member 13. The member 13 is provided with counter-sunk openings 14, so that the member 13 may be screwed or 80 fixed to the frame 10. The heads of the screws are designed to be flush with the upper surface of the member 13. Fixed on the sash 11 is a member 15, the member 15 also has counter-sunk openings 16, so that the 85 member 15 may be secured or fixed to the sash 11.

The member 13 has formed on its lower end a hook portion 17. The hook 17 of the member 13 is designed to be received in the opening 18 of the member 15. The opening 18 has a notch or groove in its lower side 19, the purposes of which will be more fully set forth. Across the upper end of the member 15 directly above the opening 18 is the portion 19^a, which is rounded substantially as is shown in Fig. 4, so that it may be received in the hook 17 of the member 13. The sash 11 may be swung outwardly, the portion 19 and the hook member 17 forming a 100 hinge. The sash may be swung outwardly substantially as is shown in dotted lines in Fig. 2 of the drawings.

The member 15 has the curved, outwardly extending portion 20. The lower end of the member 15 sets adjacent to the sash 11, while the upper end above the curved portion 20 is spaced from the sash. Fixed in the upper member 13 is a screw 21, having a head thereon 22. The screw 21 is received within 110 a screw-threaded opening in the member 13. A locking device 23 is pivotally and slidably

received between the member 13 and the head of the screw 22. The locking device or closure member 23 has an elongated slot 24 therein. The screw 21 is received in the slot 24, whereby slidable and pivotal movement of the closure member 23 relative to the base 13 is permitted. The closure member 23 has a portion attached to be received against the member 13. Spaced between the ends of the closure member 23 is a curved raised portion 25. The portion 26 of the closure member 23 is spaced from the member 13.

The hook member 17 on the lower end of the member 13 extends outwardly until its outer surface touches the inner side of the spaced portion 26 of the closure member 23, substantially as is shown in Figs. 2 and 4 of the drawings. Spaced lugs 27 and 28 are formed on the member 13 adjacent to the closure member 23 when the closure member is in its closed position, as is shown in Fig. 3 of the drawings. The lug 28 prevents any pivotal movement of the closure member in one direction, and the lug 27 prevents any pivotal movement when the closure member or locking device is in the position shown in Fig. 2. In order to disengage the locking device, it is necessary to move it vertically, upwardly until the portion 26 is aligned with the lug 27. The lug 27 extends forwardly a certain distance, so as to permit the portion 26 of the locking device 23 to pass over it, when the locking device is moved upwardly. When the locking device is in its upper position, as is shown in dotted lines of Fig. 3, the lower end of the locking device may be swung to one side, the member 26 passing over the lug 27, until the upward part of the locking device 23 strikes against the lug 28. By then moving the locking device in its inclined position, so that the portion which abuts the member 13 is placed against the lug 27, this will hold the closure member 23 from downward movement.

The member 15 may be lifted off the hook 17 by raising the member 15 upwardly and at the same time moving the sash outwardly a slight distance. The hook 17 is inclined so that there is a tendency for the portion 19^a of the member 15 to always be held inwardly against the member 13. By making the hook 17 inclined the member 15 may easily be disengaged therefrom and at the same time holds the portion 19^a of the member 15 from any accidental displacement. When it is desired to move the locking device to operative position, that is to have the portion 26 engage the hook 17, the closure member is moved to position which will permit the member 26 to pass over the lug 27, and then by gravity the locking device will fall into its proper position. The lugs 27 and 28 form guides for the locking device.

65 The opening 18 in the member 15 is of

such size as to permit the member 15 to be raised upwardly such a distance, so that the portion 19^a will be above the hook 17 and then by a slight outward movement the parts will be disengaged. The opening 18 70 also permits pivotal movement without interfering with the lower end of the closure device, when it is desired to swing the sash outwardly for any purpose such as dusting or cleaning the outside window.

75 The notch or groove 19 is specially adapted, when the device is nested for shipment, as is shown in Fig. 7, to receive the head 22 of the screw 21. The offset portion 20 of the member 15, and the offset or grooved portion 25 of the locking device are so arranged that when the device is nested, it will occupy a comparatively small amount of space, and so hold the device in such position, that it may readily be wrapped or packed for shipment.

Some changes may be made in the construction and arrangement of the various parts of my improved device without departing from the essential features and purposes of my invention, and it is my intention to cover by my claims any modified forms of structure or use of mechanical equivalents which may be reasonably included within their scope.

90 I claim as my invention:

1. In a device of the class described, a member adapted to be permanently fixed to a window casing, a second member adapted to be permanently fixed to a sash, 100 said first and second members having coacting parts whereby said second member may be pivotally mounted on said first member, and a locking means slidably and rotatably mounted on said first member 105 adapted to prevent accidental displacement of said second member relative to said first member.

2. In a device of the class described, a member adapted to be permanently fixed 110 to a window casing, a second member adapted to be permanently fixed to a sash, said first and second members having coacting parts whereby said second member may be pivotally mounted on said first member, 115 a locking means slidably and rotatably mounted on said first member adapted to prevent accidental displacement of said second member relative to said first member, and means for locking said locking means 120 in an inoperative position.

3. In a device of the class described, a member adapted to be permanently fixed to a window casing, said member having a locking device slidably and rotatably mounted thereon, spaced forwardly projecting lugs disposed adjacent to either side of said locking device, when the locking device is in its locked position, said lugs forming means whereby said locking device may 130

- be selectively held in two predetermined positions for preventing pivotal movement thereof, a hook on said member, a second member adapted to be permanently fixed to 5 a sash, said last member having means thereon for coacting with said first member, said locking device forming means for holding said second member in position relative to said first member.
- 10 4. A sash holder comprising a pair of coacting members, one of said members being adapted to be fixed to a window casing and the other of said members being adapted to be fixed to a sash, a pin secured in said first member, a locking device having an elongated slot therein adapted to receive said pin, lugs spaced adjacent to either side of said locking device forming guide members for holding said locking device in operative position, said locking device being so designed that in order to rotate said locking device upon said pin, said locking device must first be moved to its limit of vertical movement and means for locking said locking device in an inoperative position.
- 15 5. In a device of the class described, a member adapted to be fixed to a window casing or the like, a second member adapted to be fixed to a sash, said members having coacting parts whereby pivotal movement of said members relative to each other is permitted, said first member having spaced lugs thereon the upper surface of one of said lugs lying in a different horizontal plane 20 from the upper surface of the other of said lugs, a locking device mounted between said lugs, said lugs limiting the pivotal movement of said locking device to two predetermined positions.
- 25 6. In a device of the class described, a member adapted to be fixed to a window casing or the like, a second member adapted to be fixed to a sash, said members having coacting parts whereby pivotal movement of said members relative to each other is 30 permitted, said first member having spaced lugs thereon, a locking device pivotably mounted between said lugs, an elongated slot in said locking device, said locking device being capable of vertical movement 35 relative to said first member, said lugs forming guides for holding said locking device in position and forming means for permitting pivotal movement in one direction only and for limiting the pivotal movement. 40
7. In a sash hanger, a base adapted to be secured to a window casing, a hook member extended therefrom, a locking device slidably and rotatably mounted on said base adapted to form a closure member for said hook when in one position said locking device comprising a central portion having offset flanges extended in opposite directions therefrom, lugs adapted to limit the pivotal movement of the locking device 45 when the latter is in either of two predetermined positions, and a member similar in shape to the locking device adapted to coact with the hook and a sash to support the latter, whereby the last described member may be placed with one surface contiguous with a surface of the locking device to cause the entire device to occupy a minimum amount of space when packed for shipment. 50
